(57) **CLAIM**

The ornamental design for a handle and grip for a dental instrument, as shown and described.

DESCRIPTION

FIG. 1 is an isometric view of a handle and grip for a dental instrument showing the new design;

FIG. 2 is a left side elevation view of the invention illustrated in FIG. 1;

FIG. 3 is a right side elevation view of the invention illustrated in FIG. 1;

FIG. 4 is a front elevation of the invention illustrated in FIG. 1;

FIG. 5 is a back elevation view of the invention illustrated in FIG. 1;

FIG. 6 is an enlarged top plan view of the invention illustrated in FIG. 1; and,

FIG. 7 is an enlarged bottom plan view of the invention illustrated in FIG. 1.

The broken lines in the drawings depict environment, or portions, of the handle and grip for a dental instrument that form no part of the claimed design.

1 Claim, 4 Drawing Sheets
